UNITED STATES PATENT OFFICE.

JAY A. HEIDBRINK AND CHARLES W. FLETCHER, OF MINNEAPOLIS, MINNESOTA;
SAID FLETCHER ASSIGNOR TO SAID HEIDBRINK.

HEAT-CONTROLLING APPARATUS FOR ELECTRICAL FURNACES.

Application filed April 21, 1921. Serial No. 463,260.

To all whom it may concern:

Be it known that we, JAY A. HEIDBRINK and CHARLES W. FLETCHER, citizens of the United States, residing at Minneapolis, in the county of Hennepin and State of Minnesota, have invented certain new and useful Improvements in Heat-Controlling Apparatus for Electrical Furnaces, of which the following is a specification.

Our invention relates to heat controlling apparatus for electrical furnaces. The type of furnace which we have in mind particularly is that employed by dentists for burning out invested models in moulds which are to be used for making dental castings. An object of our invention is to provide for maintaining a constant temperature in a furnace heated by an electrical resistance device by synchronously controlling the passage of current through said resistance device and through a resistance coil associated with a thermostat which, by its expansion automatically cuts off the current from both resistances when the temperature in the furnace reaches a desired maximum and which, by its contraction, re-establishes the passage of current through the resistances. Another object is to provide means by which the temperature to be maintained in the furnace may be varied at will so that the desired maximum may be greater or smaller as desired. An object in general is to provide thermostatic means for controlling the amount of electrical energy delivered to an electrical element or device over an extended period of time regardless of variations in the voltage of the source of energy. The full objects and advantages of our invention will appear in connection with the detailed description, and the novel features embodied in our inventive idea will be particularly pointed out in the claims. In the accompanying drawings which illustrate a practical embodiment of our invention,—Fig. 1 is an elevational view of our apparatus connected to an electrical dental furnace, the latter being shown in vertical section. Fig. 2 is a vertical sectional view of our apparatus. Fig. 3 is a view of a slight modification, the upper portion of this view being in section corresponding to that shown in Fig. 2 and the lower portion having the outside casing plate in place. Fig. 4 is a view in vertical section on the line 4—4 of Fig. 2. Fig. 5 is a view in hori-

zontal section on the line 5—5 of Fig. 2. Fig. 6 is a view in horizontal section on the line 6—6 of Fig. 2. Fig. 7 is a view in horizontal section on the line 7—7 of Fig. 2. Fig. 8 is an end view of a commutator. Fig. 9 embodies a wiring diagram showing the passage of current at the beginning when the thermostat is cold and in contracted position. Fig. 10 embodies a wiring diagram showing the passage of electric current through divided circuits when the device has been placed in its operative position by means of a current passing through a solenoid. Fig. 11 embodies a wiring diagram showing the passage of current through the solenoid when the thermostat has been fully expanded.

Referring to the construction shown in the drawings, the letter F in Fig. 1 designates in general an electrical furnace such as that disclosed in the patent to T. W. Maves, Reissued Number 14,730, in the lower portion of which is a resistance device or coil 12, the ends of which are connected by wires 14 and 16 with metallic bars 18 and 20 respectively. As shown in Fig. 1, the furnace is lined with heat insulating material. A main wire 22 is connected to the bar 18 and the other main wire 24 is connected to a bar 26. These three bars and also a fourth bar 28 are secured in spaced relation to a piece of insulating material 30 which is secured to the inside of one of the walls of a casing 32 as best shown in Figs. 2 and 4. This casing is divided by a horizontal partition 34 into lower and upper compartments 36 and 38. The walls of the upper compartment 38 are lined with heat insulating material 40 and mounted in this compartment is a thermostat, the fixed members 42 and 44 of which are adjustably mounted in posts 46 and 48 which are insulated from the casing. The movable member 50 of the thermostat is insulatively mounted so as to lie between the members 42 and 44 and is connected by a wire 52 with the bar 28. Rotatably mounted in the lower compartment 36 is a commutator which includes a cylinder 54 of insulating material in the periphery of which are embedded three equally spaced contact plates 56. Secured to rotate with the cylinder 54 is a ratchet disk 58 having six teeth around its periphery. Oscillatingly mounted at one of

110

its ends on a trunnion of the cylinder 54 is an arm 60 which carries a pawl 62 adapted to engage the teeth of the ratchet disk. The other end of the arm 60 is pivotally connected with the lower end of a solenoid core 64 which is adapted to cooperate with a solenoid 66 having a coil 68, the ends of which are connected by wires 70 and 72 with the bars 28 and 18 respectively. Insulatively mounted above the commutator cylinder 54 in spaced relation to each other and adapted to be bridged by the contact plates 56 as they are rotated are a pair of contact fingers 74 and 76, the finger 74 being connected by a wire 78 with the bar 26 and the finger 76 being connected by a wire 80 with the post 48 of the thermostat. Insulatively mounted below the cylinder 54 in spaced relation to each other and adapted to be bridged by the contact plates 56 during their rotation are a second pair of contact fingers 82 and 84, the finger 82 being connected by a wire 86 with the bar 20 and the finger 84 being connected by a wire 88 with the finger 74. The four fingers are secured to a plate of insulating material 89. The post 46 of the thermostat is connected by a wire 90 with the bar 20, and the bar 18 is connected by a wire 92 with one end of a resistance coil 94, the other end of which is connected by a wire 96 to the wire 90 at a point near the attachment of the latter to the post 46 or it may be attached directly to this post. The movable member 50 of the thermostat is attached to a cylindrical block 98 of insulating material. Secured to this block is an arm 100, the free end of which is attached to a rod 102 having a threaded portion engaging the internally threaded surface of a sleeve 104 which carries a knob 106 on its outer end. The sleeve 104 extends through a bearing member 108 held in an opening in the casing by a nut 110 and the sleeve 104 is rotatably held by a nut 112 threaded upon its inner end and engaging the inner end of the bearing member 108. In the slight modification shown in Fig. 3, the posts 46 and 48 are insulatively mounted on a triangular plate 114 pivoted at 116. A rod 118 is attached to this plate and the outer end of this rod is attached and connected up for operation in the same manner as the rod 102. It is obvious that upon turning the knob 106 in either of these forms, the relation of the movable member and the fixed members of the thermostat will be changed so that the thermostat may be made to operate at different temperatures whereby the constant temperature to be maintained in the furnace may be varied as desired.

The operation and advantages of our invention will be readily understood from the foregoing description. The articles to be heated are placed in the furnace F and the current from the main line is turned on. Assuming that the thermostat is cold and the fingers 74 and 76 are bridged by one of the contact plates 56 as shown in Fig. 9 current 70 will pass from the main line 22 through the bar 18, wire 72, solenoid coil 68, wire 70, plate 28, wire 52, movable contact member 50, wire 80, finger 76, contact plate 56, finger 74, wire 78, bar 26, and main line 24. The current passing through the solenoid coil 66 causes its core 64 to be drawn up and move the cylinder 54 through one-sixth of a rotation which removes the contact plate from engagement with the fingers 74 and 76 and causes a contact plate 56 to bridge the fingers 82 and 84 as shown in Fig. 10. The circuit through the solenoid coil 68 is broken thereby and the core 64 will drop by gravity. The current from the main line 22 then passes to the bar 18 where it divides. One portion of the current goes through the wire 14, resistance coil 12, and wire 16 to the bar 20. Another portion goes from the bar 18 through the wire 92, resistance coil 94, wire 96 and wire 90 to the bar 20 where it joins the current through the other circuit, and the combined current passes through the wire 86, finger 82, contact plate 56, finger 84, wire 88, wire 78, bar 26 and main line 24. The current passing through the resistance coil 12 heats the furnace, and the current passing through the resistance coil 94 heats the thermostat and causes it to expand. When the desired maximum temperature in the furnace is reached, depending upon the setting of the thermostat, the movable thermostat member 50 engages the fixed member 42 as shown in Fig. 11. Current then passes from the main line 22 through the bar 18, wire 72, solenoid coil 68, wire 70, bar 28, wire 52, movable thermostat member 50, wire 90, bar 20, wire 86, finger 82, contact plate 56, finger 84, wire 88, wire 78, bar 26 and main line 24. The current is thereby shunted so as not to pass through the resistance coils 12 and 94, and at the same time the current through the solenoid coil 68 draws up the coil 64, causing the cylinder 54 to rotate another one-sixth of a revolution and removes the contact plate 56 from engagement with the fingers 82 and 84 and brings a contact plate 56 into engagement with the fingers 76. This operation cuts off all current through the apparatus and the core 64 drops by gravity. The current remains off until the movable thermostat member 50 contracts sufficiently to engage the fixed member 44 when the elements will again be in the position shown in Fig. 9 and the cycle of operations previously described will be repeated. The movable thermostat member 50, therefore, oscillates between the fixed members 42 and 44, and since the thermostat is sensitive to small 130

variations in temperature, the temperature in the furnace will be maintained substantially constant. It will be understood that when our controlling apparatus is used in connection with a furnace, the furnace chamber as well as the chamber containing the thermostat should be surrounded with heat insulating material. However, the amount of electrical energy delivered to the element or device receiving electricity will be the same whether or not said element or device is protected with heat insulating material.

We claim:

1. A heat controlling apparatus for furnaces heated by an electrical resistance device comprising a thermostat, a circuit for said electrical resistance device, an electro-magnetic device, an armature adapted to be partially rotated each time said electro-magnetic device is energized, means for causing current to flow through said resistance device when said armature is positioned in one manner and for causing current to be cut off when said armature is given a partial rotation into another position, and connections associated with said thermostat and said electro-magnetic device whereby the latter will be energized both when the movable member of said thermostat is expanded into contact with one of the fixed members thereof and when it comes into contact with the other of the fixed members thereof.

2. A heat controlling apparatus for furnaces heated by an electrical resistance device comprising a thermostat, a resistance coil adjacent said thermostat, an electro-magnetic device, circuits through said resistance device and said resistance coil, an armature adapted to be partially rotated each time said electro-magnetic device is energized, means for causing current to flow through said resistance device and said resistance coil when said armature is positioned in one manner and for causing the current to be cut off when said armature is given a partial rotation into another position, and connections associated with said thermostat and said electro-magnetic device whereby the latter will be energized both when the movable member of said thermostat is expanded into contact with one of the fixed members thereof, and when it contracts into contact with the other of the fixed members thereof.

3. A heat controlling apparatus for furnaces heated by an electrical resistance device comprising a thermostat, a resistance coil adjacent said thermostat, an electro-magnetic device, a movable member, a plurality of spaced contact plates insulatively mounted upon said member, a pair of contact fingers located at one side of said movable member and adapted to be bridged by said contact plates, a second pair of

contact fingers located at the opposite side of said movable member and adapted to be bridged in alternation with said first contact fingers by said contact plates, means operated by said electro-magnetic device 70 when energized for imparting to said movable member a step-by-step movement, four insulatively mounted spaced bars, the second and fourth bars being connected with the main electrical line, a circuit through 75 said electro-magnetic device connected with the first and second bars, a circuit through the resistance device of the furnace connected with the second and third bars, a wire connecting one of the fixed members 80 of said thermostat and the third bar, a circuit through said resistance coil of the thermostat connecting the second bar and said last mentioned wire, a wire connecting the movable member of said thermostat and the first bar, a wire connecting the other fixed member of said thermostat and one of the first mentioned pair of contact fingers, a wire connecting the other of said contact fingers with the fourth bar, a wire 85 connecting said last mentioned contact finger with one of the second mentioned pair of contact fingers, and a wire connecting the other of said second mentioned pair of contact fingers and a wire 90 connecting the other of said second mentioned pair of contact fingers with the third bar.

4. A heat controlling apparatus for furnaces heated by an electrical resistance device comprising a thermostat, a resistance coil adjacent said thermostat, a solenoid, a rotatable armature, a plurality of equally spaced contact plates insulatively mounted around said armature, a pair of contact fingers located at one side of said armature and adapted to be bridged by said contact plates, a second pair of contact fingers located at the opposite side of said armature and adapted to be bridged in alternation 100 with said first pair of contact fingers by said contact plates, means connected with the core of said solenoid for imparting to said armature a step-by-step rotation, the extent of which is one-half the spacing between said contact plates, four insulatively mounted spaced bars, the second and fourth bars being connected with the main electrical line, a circuit through the coil of said solenoid connected with the first and second 105 bars, a circuit through the resistance device of the furnace connected with the second and third bars, a wire connecting one of the fixed members of said thermostat and the third bar, a circuit through said resistance coil of the thermostat connecting the second bar and said last mentioned wire, a wire connecting the movable member of said thermostat and the first bar, a wire connecting the other fixed member of said ther- 110 115 120 125 130

- mostat and one of the first mentioned pair of contact fingers, a wire connecting the other of said pair of contact fingers with the fourth bar, a wire connecting said last mentioned contact finger with one of the second mentioned pair of contact fingers, and a wire connecting the other of said second mentioned pair of contact fingers with the third bar.
- 10 5. A heat controlling apparatus for furnaces heated by an electrical resistance device comprising a thermostat, a resistance coil adjacent said thermostat, a solenoid, a rotatable armature, a plurality of equally spaced contact plates insulatively mounted on the periphery of said armature, a pair of contact fingers located at one side of said armature and adapted to be bridged by said contact plates, a second pair of contact fingers located at the opposite side of said armature and adapted to be bridged in alternation with said first pair of contact fingers by said contact plates, a ratchet wheel having teeth in number twice the number of said contact plates, an arm pivoted at one end, a pawl on said arm adapted to engage said ratchet wheel and turn said armature through an angular distance corresponding to one of said teeth upon each forward movement of said arm, the latter being connected at its other end to the movable core of said solenoid, four insulatively mounted spaced bars, the second and fourth bars being connected with the main electrical line, a circuit through the coil of said solenoid connected with the first and second bars, a circuit through the resistance device of the furnace connected with the second and third bars, a wire connecting one of the fixed members of said thermostat and the third bar, a circuit through said resistance coil of the thermostat connecting the second bar and said last mentioned wire, a wire connecting the movable member of said thermostat and the first bar, a wire connecting the other fixed member of said thermostat and one of the first mentioned pair of contact fingers, a wire connecting the other of said pair of contact fingers with the fourth bar, a wire connecting said last mentioned contact finger with one of the second mentioned pair of contact

fingers, and a wire connecting the other of said second mentioned pair of contact fingers with the third bar.

55

6. A heat controlling apparatus for furnaces heated by an electrical resistance device comprising a thermostat, a resistance coil adjacent said thermostat, a solenoid, a rotatable armature of insulating material having three equally spaced contact plates on its periphery, a pair of contact fingers located at one side of said armature adapted to be bridged by said contact plates, a second pair of contact plates located at the opposite side of said armature and adapted to be bridged in alternation with said first pair of contact fingers by said contact plates, a six-tooth ratchet wheel fixed to said armature, an arm pivoted at one end on a trunnion of said armature, a pawl on said arm adapted to engage said ratchet teeth and turn said armature through one-sixth of a rotation upon each forward movement of said arm, the latter being connected at its other end to the movable core of said solenoid, four insulatively mounted spaced bars, the second and fourth bars being connected with the main electrical line, a circuit through the coil of said solenoid connected with the first and second bars, a circuit through the resistance device of the furnace connected with the second and third bars, a wire connecting one of the fixed members of said thermostat and the third bar, a circuit through said resistance coil of the thermostat connecting the second bar and said last mentioned wire, a wire connecting the movable member of said thermostat and the first bar, a wire connecting the other fixed member of said thermostat and one of the first mentioned pair of contact fingers, a wire connecting the other of said pair of contact fingers with the fourth bar, a wire connecting said last mentioned contact finger with one of the second mentioned pair of contact fingers, and a wire connecting the other of said second mentioned pair of contact fingers with the third bar.
